UNITED STATES PATENT OFFICE

2,433,156

MOTOR PUMP UNIT

Albert R. Pezzillo, Philadelphia, Pa.

Application February 12, 1947, Serial No. 728,145

2 Claims. (Cl. 103—87)

1

The object of this invention is to devise a novel motor pump unit which can be connected directly in a pipe line, which can be economically manufactured with a minimum of parts, which is quiet in operation, and which will operate for a long period of time without attention.

A further object of the invention is to devise novel flexible mechanism for connecting the motor housing with the pump housing.

A further object of the invention is to devise novel mechanism for connecting the motor shaft with the impeller.

It further comprehends a novel construction and arrangement of parts to produce a motor pump unit which is very compact and of light weight.

For the purpose of illustrating the invention, I have shown in the accompanying drawings a preferred embodiment of it which I have found in practice to give satisfactory and reliable results. It is, however, to be understood that the various instrumentalities of which the invention consists can be variously arranged and organized and the invention is not limited to the exact arrangement and organization of these instrumentalities as herein set forth.

Figure 1 is a side elevation, partly in section, of a motor pump unit, embodying my invention.

Figure 2 is an end view of the pump housing with the motor removed.

Figure 3 is a sectional view, on an enlarged scale, of a flexible seal, and the impeller shaft.

Figure 4 is a top plan view with the motor removed.

Figure 5 is a transverse section of Figure 4.

Figure 6 is a sectional view of the flexible connection for the motor and pump housing.

Figure 7 is a plan view of the impeller in detached position.

Similar numerals of reference indicate corresponding parts.

Referring to the drawings:

A pump housing 1 is flanged at its intake end as at 2 and at its discharge end as at 3 to adapt it to be connected directly in a pipe line. The pump housing 1 has an intake 4 leading to a passage 5 which curves downwardly and then upwardly to communicate with the annular, pump chamber 6 having a tangential discharge to a discharge passage 7. The upper end of the pump housing is faced off as at 8 to form a seat for a closure 9.

The closure 9 has a depending, annular portion which is received in the opening 11 of the pump housing. The pump housing has threaded

2

holes 12 to receive bolts 13 which pass through the closure 9, through a sealing gasket 14 and into threaded engagement with the threaded holes to secure the closure in sealed engagement with the pump housing.

A coupling sleeve 15 is fixed to the shaft 16 of an electric motor in any conventional manner, and a depending shaft 17 has its upper portion fixed in the coupling sleeve. The coupling sleeve 15 has a clearance in an aperture 18 extending through the closure 9. The shaft 17 is mounted in a flexible seal 19 and is connected with an impeller 20 by a set screw 21. The impeller has its lower, central portion cone shaped as at 22 to direct the incoming fluid to the blades of the impeller, said impeller having curved recesses at their bottoms.

The flexible seal 19 has a cup-shaped shell 23, within which a U-shaped packing 24 is contained and provided with a spring 25 which retains the packing in contact with the impeller shaft 17. The shell 23 is swaged over a disc 26.

An electric motor 27 has a sectional housing, the sections of which are secured in assembled condition by stay rods 28. These rods 28 are in threaded engagement, at their lower ends, with metal sleeves 29 internally threaded at 30 to receive the rods 28. As seen in Figure 6, the sleeves 29 are internally threaded at 31 to receive threaded studs 32 fixed to flexible, cushioning blocks 33. The blocks 33 have depending, threaded studs 34 fixed to them and secured to the pump housing by nuts 35.

The pump housing is connected in a pipe line by couplings 36 secured to the pump housing by bolts 37 and adapted for connection in a pipe line in any desired or conventional manner, for example by the threaded opening as shown in Figure 1.

It has been found in the development of this motor pump unit that electrolytic action caused injury to some of the parts and especially to the impeller shaft 17. This has been overcome by the use of a zinc washer 38 mounted on the impeller shaft, see Figure 1.

The motor is provided with the conventional relay and over-load switch, which it has not been deemed necessary to illustrate and describe in detail.

In the operation, the impeller is driven by the motor through a flexible connection to cause a flow through the pump housing.

The motor pump unit operates without vibration due to the employment of the flexible connection between the motor housing and pump

housing and the flexible seal for the impeller shaft.

The motor housing and the pump housing are preferably made of aluminum, magnesium or other light weight castings. Having thus described the invention, what I claim as new and desire to secure by Letters Patent is:

1. In a motor pump unit, a pump housing having an inlet, an outlet and a pumping chamber open at its top, a cover plate sealed with said pump housing, closing said opening and centrally apertured, a fluidtight, flexible seal in said cover plate aperture, an impeller in the pumping chamber, a motor having its shaft extending through said cover plate aperture with a clearance, through said seal and fixed to said impeller, said motor being positioned above said plate, and cushioning devices at a distance from said shaft, extending upwardly from the cover plate between the bottom of the motor and the top of the cover plate and constituting the sole support of the motor, and secured to the housing of said motor and to said cover plate.

2. In a motor pump unit, a pump housing having an inlet, an outlet and a pumping chamber open at its top, a cover plate closing said opening and centrally apertured, a fluidtight, flexible seal

in said cover plate aperture, an impeller in said pumping chamber, a motor having its shaft extending through said cover plate aperture with a clearance, through said seal and fixed to said impeller, said motor being positioned above said cover plate, stay rods passing through the housing of said motor, sleeves connected with the lower ends of said stay rods, and cushioning devices having upwardly extending studs connected with said sleeves and having downwardly extending studs connected with said cover plate.

ALBERT R. PEZZILLO.
